UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

JOURNAL BOX

Application filed March 28, 1925. Serial No. 18,992.

This invention relates to journal boxes for railway cars, and more particularly to the construction of spring-actuated lids therefor.

The principal object of the invention, generally considered, is the provision of what may be designated as an articulated lid construction in which foreign matter is efficiently excluded from the journal box and in which manual means are provided for energizing and deenergizing the operating spring of the lid.

An object of my invention is the provision of a journal box lid with a spring retainer articulated with respect thereto and provided with a flange or hood portion adapted to overlie the upper edge of the lid to efficiently exclude dirt and other foreign matter from the journal box.

Another object of my invention is the provision of a journal box lid with a spring retainer therefor, said retainer being provided with a cam surface thereon for engaging an intermediate portion of the spring and gradually stressing or energizing it to the desired degree.

A further object of my invention is the provision of a spring-actuated lid for journal boxes with a spring retainer formed with a relatively long operating arm whereby the spring may be conveniently stressed to the desired degree by hand without resorting to auxiliary apparatus.

A still further object of my invention is the provision of an articulated journal box lid comprising a lid proper, a spring retainer, and a pintle for pivotally connecting said members, a portion of said pintle being shaped for non-rotative engagement with a portion of the spring retainer whereby when the lid and spring retainer are moved normally as a unit, the pintle does not rotate with respect thereto. Other objects and advantages of the invention, relating to the various elements and combinations thereof, will become apparent as the description proceeds.

In the drawings illustrating my invention, the scope whereof is pointed out in the claims:

Figure 1 is a front elevational view of a

portion of the lid, showing the parts in assembled relation.

Figure 2 is a cross-sectional view on the line 2—2 of Figure 1, looking in the direction of the arrows.

Figure 3 is a sectional view on the line 3—3 of Figure 1, looking in the direction of the arrows.

Figure 4 is a side elevational view of a portion of the lid and spring retainer adjacent to the pivotal member, as shown in Figure 1.

Figure 5 is a front elevational view of a modified form of lid and spring retainer therefor.

Figure 6 is a cross-sectional view on the line 6—6 of Figure 5, looking in the direction of the arrows.

Throughout the specification and drawings, like parts are designated by like reference characters.

Referring first to the construction illustrated in Figures 1 to 4, inclusive, a journal box is designated by the reference character 1. Said box is preferably of the standard A. R. A. construction and has on its upper surface 2 and adjacent the forward edge thereof, a hinge lug 3, which is perforated at 4, for the passage of a hinge bolt or pintle 5 therethrough. This lug is provided at its front and top with flat faces 6 and 7, respectively, for cooperation with a spring-pressed portion carried by the lid 8 for holding the same in either open or closed position.

The lid or closure member 8 is preferably formed of pressed metal and is provided with loops or ears 9 and 10 surrounding the ends of the pintle 5, whereby the same is maintained in hinged relation with respect to the journal box. Both loops 9 and 10 are preferably provided with apertures, elongated transversely with respect to the lid, as shown in Figures 2 and 4, so as to allow some play to insure the accurate seating of the lid on the journal box. The spring retainer 11, which is a part of the lid assembly, is formed with cooperating ear or loop portions 12 and 13 also surrounding the pintle 5 for pivotally connecting said retainer with the journal box and also with respect to the lid 8.

A spring 14 is provided between the re-

tainer 11 and the lid 8 whereby the same is maintained in stressed or energized position. As illustrated, said spring preferably comprises a plurality of coiled portions 15 and 16 joined by a relatively straight portion 17 forming, in effect, the top end of the spring, upon which is preferably mounted a roller or other anti-friction device 18 which engages the hinge lug 3 and alternately presses 10 against the faces 6 and 7 thereof when in closed and open positions, respectively. The ends of the spring 14 preferably extend downwardly where they are bent towards each other at 19 and 20, and retained in pivotal 15 relation, with respect to the lid 8, by means of a clamping plate 21 preferably attached to the lid 8 by means of a rivet 22.

When the spring member 14 is free, as when the spring retainer 11 is moved away 20 from the lid 8, the roller 18 exerts no pressure on the hinge lug 3 and does not function to hold the lid in the desired relation with respect to the journal box. When, however, the spring retainer 11 is moved to the 25 position shown in the drawings, the curved or cam surface or surfaces 23 thereon, engage the coils 15 and 16 of the spring and gradually stress and move the same to the position shown in Figure 2, when said spring 20 is locked or maintained in position in the pocket or pockets 24 in the retainer 11.

In order that the spring retainer 11 may be moved without difficulty, it is provided with a relatively long operating arm 25 which 35 extends well beyond the clamping plate 21 on the lid so as to provide sufficient leverage for conveniently operating the spring retainer, by hand, to the position shown in Figure 2, without the necessity of resorting to auxiliary means. The operating lever or arm 25, however, may be perforated at 26 and 27, so that if desired, an operating bar may be inserted to more conveniently move said spring retainer to or from the position shown in Figure 2 to respectively energize or deenergize 45 the spring 14. The lid 8 desirably has an inwardly embossed portion providing an outwardly opening pocket into which the lower portion of the lever 25 extends, thereby 50 avoiding any undue projection thereof beyond the outer face of the lid.

In order to maintain the pintle or hinge pin 5 in the same position with respect to the lid 8 and spring retainer 11, when in normal 55 operation, the pintle 5 is preferably formed with a flattened or non-circular end 28 which engages a corresponding loop 12 on the spring retainer. In this way the pintle may be longitudinally moved with respect to the 60 spring retainer and lid but is prevented from pivotal motion with respect to said retainer by the non-rotative association with the hinge lug or loop 12 of the spring retainer.

The ear or loop 9 of the lid is formed, as shown, larger than the ear or loop 10 so that

the pintle 5 may be positioned by inserting it from left to right, small end first, and locking it in place by bending a tab 30 to the position shown in Fig. 1, where it closes the outer end of the loop 9. If the tab 30 on the loop 10 becomes broken off the pintle 5 may be locked in place by means of a cotter or other locking device inserted through an aperture 30^a in the circular end thereof. The ear or loop 9 of the lid 8, although not necessarily circular, is formed of such a size, as shown in dotted lines in Figure 2, that the flattened or non-circular end 28 of the pintle 5 may be rotated with respect thereto.

The side edges of the lid 8 are preferably formed with downwardly extending flanges 31 and 32 and the lower edge thereof is preferably formed with a lip 33 for conveniently opening and closing said lid. If formed of pressed metal, the lid is preferably corrugated, as shown, for rigidifying the same.

The upper portion of the spring retainer 11 is preferably rearwardly extended, as shown in Figure 2, forming a flanged or hooded portion 34 which overlies and houses the roller member 18, the upper edge of the lid 8 and the lug 3 for excluding dirt, water and other foreign matter from the journal box. The rearward edge of this flange or hood 34 is preferably reinforced by means of a rib 35 which also serves for draining water both ways from the flange 34.

When assembled as shown in these figures, the construction of the various parts is such that an operator may open the lid by grasping either the lip 33 or the spring retainer 11 at the end of the operating arm 25 thereof. That is, the force required to move the spring retainer with respect to the lid is greater than that required to move the lid with respect to the journal box, as will be understood.

In Figures 5 and 6, a modification of my invention is illustrated, in which a lid 8^a is shown pivotally connected with respect to the journal box by means of a pintle 5 which is of similar construction to that described in connection with Figures 1 to 4, inclusive. The spring retainer 11^a, however, although pivotally connected with respect to the journal box and lid 8^a in a manner similar to that heretofore described, is otherwise different in the following respects.

It is not normally adapted for pivotal motion with respect to the lid 8^a when the pintle 5 is in place because it is then held in fixed relation with respect to said lid by means of a clamping plate 21^a, preferably secured to said lid by a rivet 22^a. This is effected by the provision of a flange or hook 36 on the spring retainer which is inserted beneath the plate 21^a before the pintle or hinge pin 5 is put in place. The spring 14^a is, in this modification, formed as heretofore, with a plurality of coiled portions 15^a and 16^a, a rela-

tively straight connecting portion 17^a, however, being provided with a wear plate 18^a, instead of a roller, in accordance with the first modification.

5 The ends of the spring are only continued downwardly a short distance and are there engaged in pockets 37 and 38 in the spring retainer 11^a, rather than as heretofore being clamped to the lid. When in operating position, the spring 14^a is held between pocket 24^a on the spring retainer and extends in the pocket 39 in the lid 8^a.

10 The operation of stressing or energizing the spring 14^a is somewhat different from that described in connection with that of the first modification, in that it is necessary to insert the spring in position between the lid and spring retainer before the pintle or pivot pin is put in place, but with the hook 36 on the spring retainer engaging beneath the clamping plate 21^a, as shown in Figure 6. The upper end of the spring retainer 11^a is then forced to position, as shown in Figure 6, thereby energizing or stressing the spring 14^a to the desired degree.

15 Although this operation of stressing the spring may be effected by manually pressing at the top of the spring retainer, yet, if desired, a lever or bar may be inserted in the aperture 27^a and serve for the more convenient stressing of the spring. A lower aperture 26^a is also preferably provided in the spring retainer for lightening the weight thereof.

20 When in proper relation with respect to the hinge lug 3 and aperture 4 therein, the pintle 5 is then inserted through the loops 9^a and 12^a, aperture 4, and the loops 13^a and 10^a, in succession, when said pintle 5 may be maintained in position by a tab 30, as in the first modification, or by a cotter or the like inserted through aperture 30^a in the end thereof.

25 Except as specifically described in connection with Figures 5 and 6, the modification here illustrated is substantially the same as that shown in Figures 1 to 4, inclusive, a hood portion 34^a being provided, as in said first modification. A lug or reinforcement 40 may, however, be provided upon the front face of the hooded portion for reinforcing the same and acting as an abutment for an operating rod or bar in case such is used for stressing the spring member.

30 By virtue of the foregoing construction, it will be clear that I have provided a spring-actuated articulated lid construction which is readily operated by hand for energizing and deenergizing the spring and which is provided with a flanged or hooded portion acting to efficiently exclude dirt and other foreign material from the journal box.

35 A pintle or hinge pin is provided which is normally retained in fixed relation with re-

spect to the lid, whereby undesired wear therebetween is avoided. The spring pressure, tending to force the lid into operative engagement with the journal box, is exerted substantially centrally with respect to said lid and provision is made for allowing angling between said spring and lid and between said lid and journal box, so that a tight engagement will be effected between all edges of the lid and the journal box.

40 Having now described my invention, what I claim is:

1. In combination, a journal box having a hinge lug, a lid pivotally connected thereto, a spring retainer articulated with respect to said lid, a spring positioned between said lid and retainer, engaging the lug and lid respectively at its upper and lower portions, means on said retainer engaging an intermediate portion of said spring for gradually tensioning and holding said spring stressed in position upon movement of said retainer toward the lid, and a portion of said retainer formed to overlie the top edge of the lid.

45 2. In combination, a journal box having a hinge lug, a lid pivotally carried thereby, a spring retainer articulated with respect to said lid, a spring positioned between said lid and retainer and formed with portions exerting pressure on said lug and lid, respectively, to hold the lid in open or closed position, a curved element on said retainer for engaging said spring and gradually stressing and holding it in energized position, said retainer being provided with an operating extension for manually swinging the same relative to the lid for energizing and deenergizing said spring, and an angularly-extending portion overlying the top edge of the lid.

50 3. In combination, a journal box having a hinge lug thereon, a lid with retaining loops thereon, a spring retainer with cooperating loops, a hinge pintle extending through the journal box lug and the loops on the lid and retainer for connecting said members, said pintle and one of the loops on the retainer being formed to permit longitudinal, but prevent pivotal, motion therebetween and a spring positioned between said retainer and lid, engaging said lid and lug at opposite ends and engaged by said retainer at an intermediate portion.

55 4. In combination, a journal box having a hinge lug thereon, a lid with retaining loops thereon, a spring retainer with cooperating loops, a hinge pintle extending through the journal box lug and the loops on the lid and retainer for connecting said members, said pintle and one of the loops on the retainer being formed to permit longitudinal, but prevent pivotal, motion therebetween, and a spring held in stressed position between said retainer and lid, engaged by said retainer at an intermediate portion and provided with means at one end engaging the hinge lug to

hold the lid in either open or closed position, the other end of said spring being connected to said lid.

5. In combination, a journal box having a hinge lug thereon, a lid with retaining loops thereon, a spring retainer with cooperating loops, a hinge pindle extending through the journal box lug and the loops on the lid and retainer for pivotally connecting said members, said pindle being formed with a non-circular portion engaging one of the retainer loops of corresponding shape so that the pindle may be longitudinally inserted in place and will then be prevented from turning with respect to said retainer and a spring positioned between said retainer and lid, engaging said lid and lug at opposite ends and engaged by said retainer at an intermediate portion.

20 6. In combination, a journal box having a hinge lug thereon, a lid with retaining loops thereon, a spring retainer with cooperating loops, a hinge pindle extending through the journal box lug and the loops on the lid and retainer for pivotally connecting said members, said pindle being formed with a non-circular portion engaging one of the retainer loops of corresponding shape so that the pindle may be longitudinally inserted in place and will then be prevented from turning with respect to said retainer, and spring means held in energized position between retainer and lid, an end portion thereof alternately engaging different faces on the hinge lug to hold the lid in open or closed position, the other end engaging said lid while an intermediate portion is engaged and held in stressed position by a corresponding portion of said retainer.

40 7. In combination, a journal box having a hinge lug thereon, a lid with cooperating hinge loops, a spring retainer likewise provided with hinge loops, a hinge pindle extending through said hinge lug and all of said hinge loops for pivotally connecting said members, a torsion spring positioned between said retainer and lid and formed with a coiled portion engaging the retainer and extensions engaging the lid and hinge lug, respectively, and an extension on said retainer overlying the top edge of said lid.

45 8. In combination, a journal box having a hinge lug thereon, a lid with cooperating hinge loops, a spring retainer likewise provided with hinge loops, a hinge pindle extending through said hinge lug and all of said hinge loops for pivotally connecting said members, a spring positioned between said lid and retainer, engaging said lid and lug adjacent its ends and adapted to be engaged by said retainer intermediate its ends for energizing the same, and a relatively long operating extension on said retainer whereby said spring may be manually energized with-

out difficulty by grasping said extension and swinging said retainer toward the lid.

9. In combination, a journal box having a hinge lug thereon, a lid with cooperating hinge loops, a spring retainer likewise provided with hinge loops, a hinge pindle extending through said hinge lug and all of said hinge loops for pivotally connecting said members, spring means positioned between said lid and retainer, engaging said lid and lug adjacent its ends and adapted to be engaged by said retainer intermediate its ends for energizing the same, means operatively connecting one end of said spring means to the lid and a portion of said retainer extending beyond said connecting means for manually swinging said retainer toward and away from said lid for energizing and deenergizing said spring means.

10. In combination, a journal box, a lid, a spring retainer, means pivotally connecting said box, lid and retainer, a torsion spring positioned between said lid and retainer, engaging the latter at an intermediate portion thereof, and holding it in closed position, the ends of said spring respectively engaging the lid and hinge lug, and an extension on said retainer overlying the top edge of said lid.

11. In combination, a journal box, a lid, a spring retainer, means pivotally connecting said box, lid and retainer, an extension on said retainer overlying the top edge of said lid, a spring engaging the box and lid at opposite ends and engaged at an intermediate portion and pressed toward said lid by said retainer, and a relatively long extension on said retainer for the manual operation thereof.

12. In combination, a journal box, a lid, a spring retainer, means pivotally connecting said box, lid and retainer, an operating torsion spring energized between said retainer and lid, by engagement of a cam portion of said retainer with an intermediate portion of said spring and, when energized, acting to hold said retainer in closed position with respect to said lid, and an angularly disposed extension on said retainer, overlying the top edge of said lid.

13. In combination, a journal box having a hinge lug, a lid pivotally carried thereby, a spring retainer pivoted for normal swinging movement with respect to said lid and provided with an operating arm normally overlying the outer face of said lid and extending below the center of said lid to provide a handle for manual operation, said lid being formed with an inwardly embossed portion providing an outwardly opening pocket into which the lower portion of said handle extends, a spring positioned between said lid and retainer and formed with portions exerting pressure on said lug and lid respectively to hold the lid in open or closed position, and a cam element on said retainer for engaging said

spring, upon swinging said retainer toward the lid, for gradually stressing and holding it in energized position.

14. In combination, a journal box having a hinge lug, a lid pivotally carried thereby, a spring retainer pivotally mounted with respect to said lid, a spring positioned between said lid and retainer, one end of said spring acting on said lug and the other end acting on said lid to hold the lid in open or closed position, and cam means on said retainer for engaging said spring and gradually stressing the same, said cam means having an operating arm, said lid having an inwardly embossed portion receiving the free end of said arm.

15. In combination, a journal box having a hinge lug, a lid assembly carried thereby and comprising a closure member, a spring retainer articulated with respect to said closure member, provided with hinge loops and a torsion spring disposed between said retainer and closure member and formed with coil portions engaged by said retainer, and upper and lower portions respectively engaging the hinge lug and closure member, and a hinge pintle extending through said lug and loops for pivotally connecting the assembly to said lug, said assembly being provided with means overlying said lug and housing the upper portion of the spring.

In testimony whereof I affix my signature.
DONALD S. BARROWS.
